RUG-MAKING ATTACHMENT FOR SEWING MACHINES

John D. Karle, Roselle Park, N. J., assignor to
The Singer Manufacturing Company, Elizabeth,
N. J., a corporation of New Jersey

Application November 19, 1935, Serial No. 50,511

14 Claims. (Cl. 112—101)

This invention relates to sewing machine attachments for forming and presenting loops of a strand of yarn or the like to the needle of a sewing machine which stitches the looped strand to a base fabric in the production of rugs and various decorative effects.

The invention aims to improve the rug-making attachment forming the subject of U. S. patent application of Heinrich Perkins, Serial No. 9,553; filed Mar. 6, 1935; to gain certainty and uniformity of operation, improved wearing and operating characteristics, and to enable rows of yarn-loops to be stitched in any desired and evenly spaced relationship by an unskilled operator.

With the above and other objects in view, as will hereinafter appear, the invention comprises the devices, combinations and arrangements of parts hereinafter set forth and illustrated in the accompanying drawings, of a preferred embodiment of the invention, from which the several features of the invention and the advantages attained thereby will be readily understood by those skilled in the art.

In the accompanying drawings, Fig. 1 is a front elevation of a rug-making attachment embodying the invention and applied to a conventional sewing machine; the yarn-laying member being shown at one extreme position of its oscillatory movement. Fig. 2 is a similar view showing the oscillatory yarn-laying member at its other extreme position. Figs. 3 and 4 are left side elevations of the device with the parts in the positions of Figs. 1 and 2, respectively. Fig. 5 is a bottom plan view of the attachment. Fig. 6 is a perspective view of a yarn tensioning spring carried by the yarn-laying member. Fig. 6a is a detail view of the yarn-tensioning device. Figs. 7 and 8 are horizontal sectional views showing the looping action of the yarn-laying member in cooperation with the sewing machine needle and loop-detaining finger spaced laterally of such needle. Fig. 9 is a top plan view of the attachment. Fig. 10 is a perspective view of the pivoted follower piece which slidably engages the horizontal actuating pin on the needle-bar. Fig. 11 is a fragmentary rear elevation of the driving connection between the needle-bar and the oscillatory yarn-laying member. Fig. 12 is a rear elevation of the attachment. Fig. 13 is a section through the shank of the loop-detaining finger taken on the line 13—13, Fig. 1. Fig. 14 is a section on the line 14—14, Fig. 12. Fig. 15 is a plan view of a portion of a rug formed by use of

the attachment and Fig. 16 is a section of the rug shown in Fig. 15.

The sewing machine to which the invention is applied is conventional and comprises the reciprocating needle 1, needle-bar 2, presser-bar 3, 5 throat-plate 4, and feed-dog 5.

The attachment is constructed with a foot portion 6 having a shank 7 attachable to the sewing machine presser-bar 3 by means of the conventional presser-foot fastening screw 8. The foot portion 6 is upturned at its forward free end to form the post 9 having a lateral extension 9'. Secured to the post 9 by screws 10 is the shank 11 of the tread member 12 having a lower work-engaging face 13 and a guard-flange 14 at one side of and at an elevation above the plane of the face 13; the guard-flange having an opening 15 therein. The foot 6 has a needle-aperture 16, Fig. 5, and the tread-member 12 is formed with the rearwardly opening stitch-receiving slot 17.

There is secured to the forward face of the tread-shank 11, by means of the screw and slot expedient 18, the laterally adjustable shank 19 of a guide-member 20 having a work-guiding edge 21 rounded at 22.

The post 9 carries at its upper end the internally threaded fulcrum stud 23, Fig. 14, on which is journaled between the spacing washer 24 and spring-washer 25 the cross-bar 26 of the open 30 segmental yarn-laying member 27 formed with the yarn-delivery aperture 28 and carrying the self-threading yarn-tensioning leaf-spring 29 and the yarn-receiving guide 30. A screw 23' holds the parts 24, 25 and 26 on the pivot-stud 35 23. The yarn-tensioning spring is fastened to the segmental member 27 by means of the screw 31 and its tension on the yarn strand is adjusted by the tension-adjusting screw 32; it being understood that the shank portion of the spring 40 29 is clamped tightly to the yarn-laying member 27 by the screw 31 and is sprung away from the yarn-laying member in the region of the tension adjusting screw 32, as shown in Fig. 6a.

The segmental member 27 works in the space 45 between the foot 6 and the tread member 12 in a transverse vertical plane closely in front of the path of the needle 1 and is actuated by the needle-bar 2 in the following manner. The conventional needle-clamping screw (not shown) is 50 replaced by a special needle-clamping screw 33 having a long horizontally disposed cylindrical portion 34 slidably embraced by the spaced fingers 35, 36 of a U-shaped follower member 37 which is pivoted at 38 on the cross-bar 26 of the 55

yarn-laying member 27. The follower member 37 has at its upper end a stop-finger 39 which overlies the edge of the cross-bar 26 and prevents the user from applying the follower member 37 to the cylindrical stud 34 in an inverted position. The pivot-pin 38 has a head 38' which projects into the space between the U of the U-shaped follower member and prevents accidental application of the latter upon the stud in a position 90° from the correct position.

Working in strict parallelism with the segmental yarn-laying member 27 is a loop-detaining finger 40 having a loop-taking point 41 and an inclined portion 42 immediately above such point. The finger 40 is carried by an arm 43 which crosses over the bow of the segmental member 27 and has an upward extension 44 which is formed at its upper end with a hook 45 having the opposed walls 45' engage opposite sides of the cross-bar 26 of the yarn-laying member 27. When the walls 45' of the hook 45 engage the cross-bar 26, the loop-detaining finger 40 is positively locked against displacement laterally of the plane of the bow 27 of the yarn-laying member and this causes the point 41 of the loop-detaining finger to descend in a fixed position relative to the bow 27 irrespective of wear on the pivots 23 and 48. The point 41 of the loop-detaining finger is received in the opening 15 in the guard-flange 14.

The arm 43 is adjustably fastened by the screw-and-slot expedient 46 to the carrier-arm 47 which is fulcrumed at 48 upon the lateral extension 9' of the post 9. Thus the loop-detaining finger 35 may be adjusted laterally of the line of seam-formation to secure a desired loop-length in the product, within the limits provided. The loop-detaining finger is biased downwardly by the spring 49 which is coiled about and anchored to 40 the pivot-stud 48 and has a hooked end engaging the carrier-arm 47.

The arm carrying the loop-detaining finger 40 is provided with a finger-piece 50 for the convenience of the operator in manually disengaging 45 the loop-detaining finger 40 from the last yarn-loop preparatory to removing the work.

In the operation of the device, starting with the parts in the position shown in Fig. 1, as the needle 1 descends, the yarn-laying member 27 50 moves toward the left, and a base loop 51, of yarn, Fig. 7, is formed back of the member 27, which loop is entered by the needle. As the yarn-laying member continues its motion to the left, the base loop 51 is tightened about the needle 55 and the finger 40 is withdrawn from the previously formed tip-loop 52, Fig. 7. When the motion of the yarn-laying member is reversed by the rise of the needle-bar, a new tip-loop 53, Fig. 8, is formed and such loop is entered by the 60 descending finger 40. As this action is repeated the base loops 51 are sewn to the fabric base 54 by the line of stitches 55. The bases of the loops of the previously stitched row are guided by the edge-guide 21 and pass under the guard-flange 65 14 of the tread member 12 which protects such previously stitched loops from being caught by the point 41 of the finger 40. The feed-dog 5 13 works in conjunction with the bottom surface 13 of the tread-member to feed the work; the stitch-length being adjusted by the usual feed-regulator (not shown) to suit the thickness of the yarn and to effect the desired spacing of the loops in the row.

It will be noted in Fig. 3 that the tip-loop 53 75 which is caught by the loop-detaining finger 41

lies around the inclined shank portion 42 of such finger and, instead of lying horizontally, is twisted out of a horizontal plane so as to stand at an angle to the horizontal. This results in an even overlapping or nesting of the loops in the row, 5 like the kernels in an ear of corn, which loops are made with a high degree of uniformity resulting in an attractive product. The light tension applied to the yarn by the spring 29 also contributes to the uniform character of the loops in 10 the finished product, each loop being tensioned to the same degree in the process of its formation.

While I have shown and described in detail one embodiment of the invention, it is to be understood that the invention is not limited to details of the construction and relative arrangements of parts shown and described, as various modifications may obviously be made by those skilled in the art within the spirit and scope of the invention.

The term yarn is used herein in a broad sense and is intended to include any strand or cord or strip like material.

Having thus set forth the nature of the invention, what I claim herein is:—

1. In a rug-making attachment, a foot having an attaching shank and a horizontal work-engaging face, a segmental yarn-laying member pivotally carried by said foot for movement transversely of said foot in a vertical plane, and a loop-detaining finger fulcrumed on said foot to move up and down about an axis parallel to the pivotal axis of said yarn-laying member.

2. In a rug-making attachment, a foot having 35 an attaching shank and a horizontal work-engaging face, a segmental yarn-laying member pivotally carried by said foot for movement transversely of said foot in a vertical plane, a loop-detaining finger fulcrumed on said foot to move 40 up and down about an axis parallel to the pivotal axis of said yarn-laying member, and an actuating connection between said yarn-laying member and said finger.

3. In a rug-making attachment, a foot having 45 an attaching shank and a horizontal work-engaging face, a segmental yarn-laying member pivotally carried by said foot for movement transversely of said foot in a vertical plane, a loop-detaining finger fulcrumed on said foot to move 50 up and down about an axis parallel to the pivotal axis of said yarn-laying member, an actuating connection between said yarn-laying member and said finger, and means for interlocking said finger and yarn-laying member against relative displacement transversely of their planes of oscillation.

4. In a yarn-loop sewing attachment, a foot having an attaching shank and a tread member 60 formed with a work-engaging face and a raised guard-flange at one side of said face to clear the base portions of a previously stitched row of yarn-loops, and an oscillatory yarn-loop-forming member and a loop-detaining finger each pivotally carried by said foot.

5. In a yarn-loop sewing attachment, a foot having an attaching shank and a tread member formed with a work-engaging face and a raised guard-flange at one side of said face to clear the base portions of a previously stitched row of 70 yarn-loops, an oscillatory yarn-loop-forming member and a loop-detaining finger each pivotally carried by said foot, and an edge-guide adapted to engage the bases of the loops of the previously stitched row of yarn-loops.

6. In a yarn-loop sewing attachment, a foot having an attaching shank and a tread member formed with a work-engaging face and a raised guard-flange at one side of said face to clear the base portions of a previously stitched row of yarn-loops, an oscillatory yarn-loop-forming member and a loop-detaining finger each pivotally carried by said foot, and an edge-guide adapted to engage the bases of the loops of the previously stitched row of yarn-loops, said edge-guide being mounted on said foot for adjustment laterally of the line of seam formation.

7. The combination with a reciprocatory needle, and a feed-dog, of a presser-foot opposed to said feed-dog, a yarn-laying member carried by said foot and movable laterally of the line of feed, a loop-detaining finger carried by said foot and movable up and down in a path at one side of said needle and close to said yarn-laying member, and a yarn-tensioning spring carried by said yarn-laying member.

8. The combination with a reciprocatory needle, and a feed-dog, of a presser-foot opposed to said feed-dog, a yarn-laying member carried by said foot and movable laterally of the line of feed, a loop-detaining finger carried by said foot and movable up and down in a path at one side of said needle and close to said yarn-laying member, a yarn-tensioning leaf-spring carried by said yarn-laying member, and a screw for adjusting the tension of said spring.

9. A rug-making attachment comprising a foot having an attaching shank at its rearward end and a post at its forward end, said post having a lateral extension, a segmental yarn-laying member pivotally mounted on said post, and a loop-detaining member pivotally mounted on said lateral extension, the pivotal axis of said members being parallel.

10. A rug-making attachment comprising a foot having an attaching shank at its rearward end and a post at its forward end, said post having a lateral extension, a segmental yarn-laying member pivotally mounted on said post, a loop-detaining member pivotally mounted on said lateral extension, the pivotal axis of said members being parallel, and means whereby said loop-detaining member may be adjusted toward or away from its pivotal axis.

11. The combination with a presser-bar, a reciprocatory needle-bar, and needle, of a needle-clamp formed with a horizontally elongated head, a foot carried by said presser-bar, a segmental yarn-laying member pivotally carried by said foot, a follower pivotally carried by said yarn-laying member and embracing the head of said needle-clamp, and a loop-detaining member pivotally carried by said foot and actuated in one direction by said yarn-laying member. 10

12. A rug-making attachment for sewing machines comprising a foot having an attaching shank, a yarn-laying member pivotally carried by said foot and having a rearwardly disposed face, and a loop-detaining finger mounted on said foot for up-and-down movement in a plane closely in rear of the face of said yarn-laying member, said finger having a loop-entering point and an upwardly and rearwardly inclined shank-portion immediately above said point. 20

13. A rug-making attachment for sewing machines comprising a foot having an attaching shank and a tread member formed with a rearwardly opening stitch-receiving slot, said tread member having a lower work-engaging face and a guard-flange at one side of said stitch-receiving slot and above the plane of said work-engaging face, an oscillatory yarn-laying member carried by said foot and movable transversely of and above said tread member, and a loop-detaining finger movable up-and-down above said guard-flange and in rear of said yarn-laying member. 30

14. A rug-making attachment for sewing machines comprising a foot having an attaching shank and a tread member formed with a rearwardly opening stitch-receiving slot, said tread member having a lower work-engaging face and a guard-flange at one side of said stitch-receiving slot and above the plane of said work-engaging face, an oscillatory yarn-laying member carried by said foot and movable transversely of and above said tread member, and a loop-detaining finger movable up-and-down above said guard-flange and in rear of said yarn-laying member, said guard-flange having an opening to receive the point of said loop-detaining finger. 40 45

JOHN D. KARLE.
